ATTORNEY

UNITED STATES PATENT OFFICE.

FRED N. BIERCE, OF CINCINNATI, OHIO.

BURNER.

Application filed November 22, 1922. Serial No. 602,643.

My invention relates to burners in which coal oil or kerosene is converted into gas and mixed with air as a fuel to be used in said burner.

5 The object of my invention is to provide simple, efficient and economically constructed means for producing such a burner.

My invention consists in providing a casting having a gas chamber or a gas and air 10 mixing chamber and having extended channels with removable baffles therein for forming gas burner outlets.

My invention also consists in the construction, combination and arrangement of parts 15 as herein set forth and claimed.

In the drawings:

Fig. 1 is a perspective view of a burner constructed according to my invention with a part of the gas generator broken away 20 to more clearly illustrate the gas outlet construction;

Fig. 2 is an enlarged longitudinal section taken on the line 2—2 of Fig. 1 with one of the removable baffles omitted;

25 Fig. 3 is a side elevation of one of the baffles partly broken away;

Fig. 4 is a perspective view thereof partly broken away; and

Fig. 5 is a perspective view of a portion 30 of the burner showing one of the removable baffles lifted partly out of position.

In the embodiment of my invention as illustrated and which shows a preferred construction I provide a metal casing 1 having 35 gas and air mixing chamber 2 and having large extended channels 3 in the upper wall thereof, each channel being provided with an extended wall 4 projecting upwardly on each side and end thereof from the top wall 2' of chamber 2. The large channels permit said casing to be cast without the necessity of machining it thereby saving in cost of construction. Within each channel 3 I insert a removable rectangular trough-shaped 40 baffle 5 tapering downwardly from top to bottom to correspond with the shape of

channels 3 and cut away between its corners 6 on its sides and ends to form gas passages 7 and 8 when it is inserted into channel 3. A suitable handle 9 is mounted centrally of 50 each baffle for the purpose of conveniently handling it for insertion into and removal from position in the channel for cleaning, repairing and the like. The baffles may also be cast without machining and thereby a 55 great saving is effected in the cost of construction. By extending the walls 2' to form upwardly extending flanges 4 a long gas passage 4' is formed from the gas chamber to the point where the gas is ignited and forms flame 10 so that the upper wall 2' of gas chamber 2 is prevented from being heated to such an extent as to cause back-firing of the burners into said chamber. 60

The burner is provided with a suitable 65 generator 11 which is mounted between the rows of burners 12 and 13, respectively, and a suitable asbestos wick 14 is placed in a depression adjacent said generator between said rows of burners and may be saturated 70 with wood alcohol for the purpose of initially heating said generator.

While I have shown a particular construction and arrangement of parts it will 75 be apparent that the same is capable of modification without departing from the scope or spirit thereof as defined in the claim.

What I claim as new and desire to secure by Letters Patent is:

In a gas burner, a casing having a gas 80 and air mixing chamber, a plurality of spaced apart extended outlets projecting outwardly therefrom and arranged in rows, a gas generator disposed between said rows, and a removable baffle mounted in each of 85 said extended gas outlets and reduced on its sides and ends between its corners to form gas passages between the walls of said gas outlets and said baffle, substantially as set forth and for the purposes specified.

FRED N. BIERCE.
